INVENTOR

UNITED STATES PATENT OFFICE.

EMIL GUMBINNER, OF NEW YORK, N. Y.

DESIGN FOR A BELT AND GARMENT HOOK.

SPECIFICATION forming part of Design No. 26,505, dated January 12, 1897.

Application filed October 27, 1896. Serial No. 610,233. Term of patent 3½ years.

To all whom it may concern:

Be it known that I, EMIL GUMBINNER, a citizen of the United States of America, and a resident of New York city, New York, have 5 invented and produced a new and original Design for a Belt and Garment Hook, of which the following is a specification.

The object of this design is to provide a handsome and ornamental belt and garment hook which presents a characteristic and distinguishing appearance to the eye.

The design consists of a hook-body piece of the shape shown, and a tapering and double hook pendent from the same.

15 My new design is illustrated in the accompanying drawings, in which—

Figure 1 shows the perspective view, and Fig. 2 is a lateral view of the same.

On the drawings, A is the hook-body piece. C are hinge-sockets at the bottom edge of the 20 same, and B the double hook pendent from the body-piece.

What I claim, and desire to secure by Letters Patent, is—

The design for a belt and garment hook 25 substantially as herein shown and described.

In testimony that I claim the foregoing as my invention I have signed my name, in presence of two witnesses, this 21st day of October, 1896.

EMIL GUMBINNER.
